UNITED STATES PATENT OFFICE.

WILLIAM L. CARD AND FRANCIS W. BOSCO, OF DENVER, COLORADO, AND CLARENCE I. GLASSBROOK, OF SAN FRANCISCO, CALIFORNIA.

SIZING-CLASSIFIER.

No. 890,602.

Specification of Letters Patent. Patented June 16, 1908.

Application filed September 24, 1907. Serial No. 394,358.

To all whom it may concern:

Be it known that we, WILLIAM L. CARD, FRANCIS W. BOSCO, and CLARENCE I. GLASSBROOK, citizens of the United States, residing, respectively, at Denver, in the county of Denver and State of Colorado; Denver, in the county of Denver and State of Colorado, and San Francisco, in the county of San Francisco and State of California, have invented certain new and useful Improvements in Sizing-Classifiers; and we do hereby declare the following to be a full, clear, and exact description of the invention, such as will enable others skilled in the art to which it appertains to make and use the same.

Our invention relates to the construction of that class of apparatus, commonly termed sizing classifiers, and is especially designed for progressively sizing the granular ingredients of a stream of pulp as it flows from the stamps, Chilian mill, or other crushing device, and for delivering the several grades of pulp to the appropriate tables of a battery. By our devices the load of each table in the battery may be gaged according to the size and nature of the material fed thereto, and the several relative adjustments of each table may be permanently established whereby the best possible results are obtained with the least possible attention and expense.

The invention has for its objects the provision of simple, inexpensive and efficient means, durable in character, easily repaired by the ordinary mechanic and capable of successful operation by the ordinary mill employee, which shall be operated with the minimum amount of water supplied through the bottom of the settling chamber, and in some instances without such water supply, where it is desirable to so operate the devices.

To this end the main feature of our invention, embraces the combination with a launder section and settling chamber, of an interposed expansion chamber, and a shield or jetty which controls the intake leading from the expansion chamber to the settling chamber.

A second feature of our invention embraces the combination with a launder section and settling chamber, of an interposed expansion chamber having metallic plates which form the bottom of the expansion

chamber and the intake connecting the expansion chamber with the settling chamber.

A further feature of our invention embraces the combination with a settling chamber and an expansion chamber leading thereto, of a launder section of general V cross sectional bottom delivering into the expansion chamber, to induce stratification previous to the entrance of the pulp into the expansion chamber on its way to the settling chamber.

There are other features of invention, embracing particular combinations and special features of elemental construction, all as will hereinafter more fully appear.

In the drawings chosen for the purpose of illustrating our invention, the scope whereof is pointed out in the claims, Figure 1 is a longitudinal section of the connecting portions of a launder, a settling chamber, and an interposed expansion chamber embodying our invention; Fig. 2 is a top plan view of portions of the launder and the expansion chamber shown in Fig. 1; Fig. 3 is a transverse vertical section of the launder on the line 3—3, Fig. 1; Fig. 4 is a transverse vertical section of the expansion chamber, the upstanding longitudinally disposed dividing jetty or double shield and the settling chamber, taken on the line 4—4, Fig. 1; Fig. 5 is a transverse vertical section of a modified form of the expansion chamber, the dividing jetty or shields omitted, the expansion chamber in this instance having a flat bottom; Fig. 6 is a plan view of a sizing classifier embodying our invention, in combination with a battery of five concentrator tables; and Fig. 7 is a rear end elevation of the sizing classifier and battery of tables shown in Fig. 6.

Like symbols refer to like parts wherever they occur.

The sizing classifier as a whole will be comprised of a plurality of expansion chambers and settling chambers arranged in series and connected by short sections of launder. The number of expansion and settling chambers will correspond to the number of concentrator tables in the battery employed.

We will now proceed to describe our invention more fully, so that others skilled in the art to which it appertains may apply the same.

In the drawings, A indicates the launder sections, B the expansion chambers, and C

the settling chambers. The launder sections A have a channel a , the bottom whereof is of tapering vertical cross-section, in order to induce stratification in the pulp previous 5 to its entry into the expansion chamber, the launder being so disposed as to deliver pulp partially stratified to the expansion chamber without disturbance of the stratification. Said section A may be in the form of a casting, yet when built up of wood the inclination 10 of the bottom faces, which are preferably equally inclined transversely to meet at an angle of ninety degrees, may be effected by the insertion of fillets a' in the corners of the trough, as shown. These fillets should be beveled or splayed at their junction with the expansion chamber B, as at a'' , to facilitate the spreading of the stream of pulp as it enters the expansion chamber, and also at their 15 leading ends, as at a''' , to cause the convergence of the stream as it leaves the expansion chamber B on its way to the succeeding expansion chamber.

The width and depth of the launder sections A may be six or eight inches more or less, and the launder sections may be connected with the interposed expansion chambers B by means of cleats a^4 and bolts a^5 , or in any other suitable manner.

30 The interposed expansion chambers B may have either a flat bottom as indicated in Fig. 5 of the drawing, or a bottom formed of faces arranged at any desired inclination. Such bottom is, however, preferably of V-shape 35 cross-section, having an included angle of about 135 degrees, as indicated in Fig. 4 of the drawing. In such case the bottom, which is formed of metallic plates b , may have said plates bedded on fillets b' if desired. 40 Through said plates b and the bottom of the expansion chamber B is formed the longitudinally disposed intake slot c of the settling chamber C, said slot being enlarged below, as at c' , to facilitate the escape of the granular 45 matter into the settling tank C.

D indicates an adjustable upstanding longitudinally disposed dividing jetty or double shield which is centrally disposed in the expansion chamber B. This double shield or 50 dividing jetty is formed of thin, diverging blades of wood or metal d joined at their front ends to a distance piece d' . The toe or projecting lower end of this distance piece extends downwardly through the intake slot c in the bottom of the expansion chamber, 55 said longitudinally disposed slot thus forming a guide for the dividing jetty and permitting the adjustment thereof longitudinally of the expansion chamber B.

60 Extending across the expansion chamber B and secured to the sides thereof by threaded bolts and thumb nuts d^2 is a clamp bar D' which, or equivalent means, may be employed for adjustably securing the dividing 65 jetty D in the expansion chamber B.

It is to be noted that the expansion chamber B is wider than the launder section A, to permit of a horizontal expansion or spread of the stream as it leaves the launder. It should preferably have a cross sectional area, after deducting the space occupied by the dividing jetty or shield D, equal to that of the launder section A. The width of the longitudinally disposed intake slot c leading to the settling chamber C is preferably from one-quarter to three-eighths of an inch, while its length is coextensive with the settling chamber, say in the neighborhood of sixteen inches. The settling chamber C is preferably a pointed or taper-box whose greatest inside length is substantially that of the slot c , its width being about three inches and its depth about twelve inches, more or less. This settling chamber is provided at its apex with a pipe flange c^2 into the threaded opening of which is screwed a short nipple c^3 that connects with a cross or T-pipe c^4 having a plug c^5 . To this T-pipe c^4 are connected the valved inlet pipe c^6 and the valved outlet or pulp pipe c^7 . The inlet pipe c^6 is connected with a pipe c^8 leading from the mill water tank, in order to supply additional water to the settling chamber when desired, and the outlet or pulp pipe c^7 is provided with a suitable pipe or conduit leading to the appropriate 95 concentrator table, T' , T^2 , T^3 , T^4 , T^5 as the case may be, to conduct the different sizes or grades of pulp to the respective tables for final separation.

As before noted, the several expansion chambers B and settling chambers C are interposed between short sections of launder A, and should be set on a down grade or at such an inclination from the first to the last of the series as will insure a current in the launder sufficient to carry the grains of solid matter in suspension. For this purpose a descending grade of from one to two inches to the foot will generally suffice. The inclination of the expansion chamber B has also the effect of causing the left hand portion (see Fig. 1) or intake of slot c to be elevated with respect to the right hand portion or outlet of slot c , thus adding to the efficiency of the devices at all times and especially when no additional supply of settling chamber water is employed.

The construction and arrangement of the devices being substantially such as hereinbefore pointed out their operation will be as follows: After the double shield or dividing jetty D of each expansion chamber B has been longitudinally adjusted in the expansion chamber to give the desired length of intake slot c (to the left of distance piece d' , Fig. 1), and when the valves of the additional water inlet pipe c^6 and the pulp outlet pipe c^7 have been so adjusted with relation to each other and to the intake slot c as to obtain the desired result or size of 130

pulp granules for that particular settling chamber and the corresponding concentrator table, the settling chamber will be filled or allowed to fill with water. The 5 pulp from the crushing devices on entering the first, or highest, launder section A (see Figs. 6 and 7) will in its passage through such section stratify or arrange itself with the coarser and heavier particles along the bottom of the V-shaped channel and with the remaining particles graded progressively in size as the surface is approached, the finest particles being at or near the surface of the stream. On leaving this launder 10 section A the stream will spread in the expansion chamber B and while the coarser and heavier particles will pass through the intake slot c (to the left of distance piece d') into the settling chamber C, the lighter and 15 smaller particles will pass with the main current on each side of the upstanding longitudinally disposed dividing jetty or double shield, D, and into the next launder section. Any of the finer particles which may be 20 carried down with the coarser and heavier material into the settling chamber will, by reason of the upward current in said settling chamber and also by reason of the intake portion of slot c being higher than the out- 25 let portion of slot c, rise or be carried upward into the slack water back of (or to the right of) the dividing jetty D and will again enter the current in the expansion chamber B on their way to the succeeding launder 30 section, expansion chamber and settling chamber.

There will be a downward current from the expansion chamber which will carry the heavier and coarser material into the settling chamber from whence it is delivered 40 to the concentrator table, and also a curved upward flow from the settling chamber into the expansion chamber which will carry the lighter and finer particles back into the current of the expansion chamber. This is 45 illustrated by the arrows in Fig. 1 of the drawings, wherein the featherless arrows indicate the course of the heavier and coarser material, and the feathered arrows that of the finer and lighter material.

The foregoing operation is repeated 50 throughout the entire series of expansion chambers and settling chambers, the deposited particles becoming successively finer until the launder water escaping from the 55 last expansion chamber of the series carries only the slimes, which may be delivered as at s, to a slime table for final treatment.

It is to be noted that if the shield or 60 dividing jetty is moved to the left (Fig. 1), the intake through slot c will be shortened so that less material will pass therethrough, and that consequently there is a proper relation to be established between the length 65 of the intake portion of said slot c, the clear

water admitted through the valve of inlet pipe c⁶ and the outlet of pulp through the plug valve outlet pipe c⁷.

It is to be understood that during the operation of the devices the adjustments of the 70 inlet and outlet valves of branches c⁶ and c⁷ should be such that all parts of the settling chamber C are kept filled with water.

It is sometimes advantageous to change the connections of the inlet for clear water c⁶ 75 and the plug c⁵ so that instead of a side flow there will be a vertical flow of water to prevent the settling and discharge of any fine pulp particles which may have entered the settling chamber C through the intake portion of slot c.

Though the several sections A, B and C of the sizing classifier are shown and described herein as constructed of wood, it will be evident that they may be constructed of metal, 85 and, if desired, may be in the form of castings without departing from the spirit or scope of our invention: and wherever herein proportions have been stated the same are to be taken as matters of suggestion and not as 90 limitations.

Among the advantages incident to the construction of our sizing classifier devices are inexpensiveness, durability, simplicity, effectiveness and capability of being repaired 95 *in situ* and by ordinary mechanics.

The advantages incident to the operation of our sizing classifier are, that it can be thoroughly understood and readily adjusted and operated by the ordinary mill employee; 100 that when once adjusted it will run for days without requiring further attention; that it can be operated successfully with a minimum of clear water admitted through the bottom of the settling chamber, or with none at all 105 where circumstances require it; and, finally, when properly adjusted the work done will nearly, if not fully, equal that done by a system of screens, without the difficulties, expense, labor and annoying delays incident to 110 the operating of a screen system.

Having thus described our invention, what we claim and desire to secure by Letters Patent is:

1. In a sizing classifier, the combination of 115 a launder portion having a bottom of tapering vertical cross - section, an expansion chamber, the launder being so disposed as to deliver pulp partially stratified to the expansion chamber without disturbance of the 120 stratification, and a settling chamber with which the expansion chamber communicates.

2. In a sizing classifier, the combination of 125 a launder portion having a bottom of tapering vertical cross section, an expansion chamber, the launder being so disposed as to deliver pulp partially stratified to the expansion chamber without disturbance of the stratification, and a settling chamber, the bottom of the expansion chamber having a 130

longitudinally disposed slot leading into the settling chamber.

3. In a sizing classifier, the combination of a launder portion having a bottom of tapering vertical cross section, an expansion chamber having a transversely inclined longitudinally slotted bottom, the launder being so disposed as to deliver pulp partially stratified to the expansion chamber without disturbance of the stratification, and a settling chamber with which the expansion chamber communicates through its slotted bottom.

4. In a sizing classifier, the combination of a launder portion having a bottom of tapering vertical cross - section, an expansion chamber having a transversely inclined longitudinally slotted metallic bottom, the launder being so disposed as to deliver partially stratified pulp to the expansion chamber without disturbance of the stratification, and a settling chamber with which the expansion chamber communicates through its slotted bottom.

5. In a sizing classifier, the combination of a launder portion having a bottom of tapering vertical cross - section, an expansion chamber having a transversely inclined slotted bottom, the launder being so disposed as to deliver pulp partially stratified to the expansion chamber without disturbance of the stratification, an upstanding longitudinally disposed dividing jetty arranged in the expansion chamber, and a settling chamber with which the expansion chamber communicates through its slotted bottom.

6. In a sizing classifier, the combination of an expansion chamber, an upstanding longitudinally disposed dividing jetty arranged in the expansion chamber, and a settling chamber with which the expansion chamber communicates.

7. In a sizing classifier, the combination of an expansion chamber, an adjustable upstanding longitudinally disposed dividing jetty arranged in the expansion chamber, and a settling chamber with which the expansion chamber communicates.

8. In a sizing classifier, the combination of an expansion chamber having a slotted bottom whereby it communicates with a settling chamber, an adjustable upstanding longitudinally disposed dividing jetty arranged in the expansion chamber, and a settling chamber.

5. 9. In a sizing classifier, the combination of an expansion chamber having a slotted transversely inclined metallic bottom, an adjustable upstanding longitudinally disposed dividing jetty arranged in the expansion chamber, and a settling chamber with which the expansion chamber communicates through its slotted bottom.

10. In a sizing classifier, the combination of a launder portion having a bottom of tapering vertical cross section, an expansion

chamber the launder being so disposed as to deliver pulp partially stratified to the expansion chamber without disturbance of the stratification, having a slotted bottom, and a settling chamber with which the expansion chamber communicates through its slotted bottom. 70

11. In a sizing classifier, the combination of a launder portion having a bottom of tapering vertical cross section, an expansion chamber having a transversely inclined slotted bottom, an upstanding longitudinally disposed dividing jetty arranged in the expansion chamber, and a settling chamber which communicates with the expansion 75 80 chamber.

12. In a sizing classifier, the combination with a launder portion having a bottom of tapering vertical cross section, of an expansion chamber having a slotted metallic bottom of tapering vertical cross-section, an adjustable upstanding longitudinally disposed dividing jetty arranged in the expansion chamber, and a settling chamber which communicates with the expansion chamber. 85 90

13. In a sizing classifier, the combination with a settling chamber, of an expansion chamber having a jetty formed with blades, said jetty being adapted to induce a current of pulp water through the settling tank from that part of the expansion chamber which is in front of such jetty to that part of such expansion chamber which lies between the blades of such jetty. 95

14. In a sizing classifier, the combination with a settling chamber, of an expansion chamber having a slotted bottom, and a jetty which divides the slot in the bottom of the expansion chamber into intake and outlet portions, said jetty having separated blades between which a portion of the said slot is located. 100 105

15. In a sizing classifier, the combination with a settling chamber, of an expansion chamber having a transversely inclined bottom, and a launder portion which is splayed at its junction with said expansion chamber. 110

16. In a sizing classifier, the combination with a settling chamber, of an expansion chamber, and a launder portion which is splayed at its junction with said expansion chamber, said launder portion being of tapering vertical cross section. 115

17. The combination with a plurality of ore concentrating tables, of a plurality of sizing classifiers arranged in series on a descending grade and connected by intermediate launder sections having bottoms of tapering vertical cross section, said sizing classifiers comprised of expansion chambers having slotted bottoms, adjustable dividing jetties arranged in the expansion chambers, and settling chambers which communicate with the expansion chambers. 120 125

18. The combination with a plurality of 130

ore concentrating tables, of a plurality of sizing classifiers, each of which classifiers has a longitudinally inclined expansion chamber having a slotted bottom, a dividing jetty arranged in said expansion chamber and a settling chamber which communicates with its expansion chamber, the several classifiers being arranged in series on a descending grade, and intermediate launder portions having bottoms of tapering cross-section which connect the expansion chambers.

19. In a sizing classifier, the combination with a launder section having a bottom of substantially **V** shape in vertical cross section, of a settling chamber, and an interposed expansion chamber having a longitudinally disposed slot whereby it communicates with the settling chamber, the launder being so disposed as to deliver pulp partially stratified 20 to the expansion chamber without disturbance of the stratification.

20. In a sizing classifier, the combination with a launder section having a bottom of substantially **V** shape in vertical cross-section, of a settling chamber, an interposed expansion chamber having a longitudinally disposed slot whereby it communicates with the settling chamber, the launder being so disposed as to deliver pulp partially stratified

to the expansion chamber without disturbance of the stratification, and a dividing jetty arranged in the expansion chamber on the line of said slot.

21. In a sizing classifier, the combination with a launder section having a bottom of substantially **V** shaped cross-section, a settling chamber, an interposed expansion chamber having a longitudinally disposed slot whereby it communicates with the settling chamber, the launder being so disposed as to deliver pulp partially stratified to the expansion chamber without disturbance of the stratification, and a dividing jetty longitudinally adjustable within the expansion chamber in the line of said slot. 45
